UNITED STATES PATENT OFFICE.

WILLIAM PHILLIPS, OF NEW YORK, N. Y., ASSIGNOR TO EUREKA RADIO AND PHONO PARTS CO., A CORPORATION OF NEW YORK.

COMBINED PHONOGRAPHIC AND TELEPHONIC APPARATUS.

Application filed November 14, 1923. Serial No. 374,615.

To all whom it may concern:

Be it known that I, WILLIAM PHILLIPS, a citizen of the United States, and resident of New York, in the county of New York and State of New York, have invented certain new and useful Improvements in Combined Phonographic and Telephonic Apparatus, of which the following is a specification.

10 My present invention relates to sound reproducers and more particularly to apparatus for use alternatively as a phonograph or as an amplifying telephone receiver, the latter application more especially for amateur 15 radio purposes.

It is an object of the invention to provide an apparatus of the above type which shall eliminate the need for mounting or dismounting the phonograph sound box or the 20 telephone receiver with respect to the tone arm in order to change over from phonograph to radio operation and vice versa, and which shall yet be capable of use at will, either as a phonograph operated by a record, 25 or as an amplifying telephone receiver or loud speaker operable from a radio receiving set.

It is another object to provide an apparatus of the above type, the operation of which will be satisfactory either as a phonograph 30 or as an amplifying telephone receiver, and which may moreover be employed to produce novel effects for simultaneous reproduction of phonograph records, synchronized if desired with complementary telephonically 35 transmitted messages or selections.

The invention has a preferred application to the substantially conventional phonograph, the tone arm only of which is modified to provide a double inlet at one of which is connected the usual sound box having a diaphragm actuated from the usual stylus, and to the other of which is attached a telephone receiver. In the preferred embodiment the entire weight of the tone arm 40 together with that of the sound box and of the telephone receiver carried thereon, is supported at the pivoted or amplifier end, so that the weight of the telephone receiver which may be permanently retained on the 45 tone arm shall not increase the pressure of the sound box stylus upon the record groove.

In the preferred application the tone arm inlet or nipple for the telephone receiver extends horizontally in axial alignment with 50 the lateral offset or nipple for the sound

box, the latter having the usual neck pivotally connected to the sound box, for raising the latter out of engagement with the phonograph record or turn table, and this without interfering with the telephone receiver.

In my copending application 689,217, filed January 29, 1924, I have presented claims to all subject matter common to the two applications.

In the accompanying drawings in which are shown one or more of various possible embodiments of the several features of this invention,

Fig. 1 is a fragmentary elevation partly in section of a preferred embodiment of the invention.

Fig. 2 is a fragmentary plan view on a larger scale and partly in section of a tone arm embodying my invention and

Fig. 3 is a fragmentary sectional view of an alternative application.

Similar reference characters refer to similar parts throughout the several views of the drawings.

Referring now to the drawings, I have shown a phonograph cabinet 10, supporting a phonograph record turn table 11 to be rotated by the usual spring or electric motor (not shown) mounted on the lower surface 85 of motor board 12. Within the cabinet is the usual amplifier 13, to the upper end of which is connected the tone arm 14. In the preferred embodiment, the tone arm is pivotally mounted upon a metal support spider 90 15 secured as by screws 16 to the motor board 12. The spider 15 has a thrust bearing 17 for a cooperating thrust bearing member 18 at the lower surface of a spider 19 in the tone arm. A pin 20 longitudinally 95 through spider 19 and secured thereto, has a bearing in a corresponding elongated hub 21 in the supports spider 15 and constitutes the pivot mount, which permits the rotary movement of the tone arm across 100 the turn table for playing a record. The tone arm is illustratively shown of the taper form, the amplifier end of which telescopes into the hub 22 of support spider 15 with small clearance 23 therebetween. The tone 105 arm has the usual laterally curved inlet 24 upon which the usual S-shaped sound box neck 25 is attached by screw 26 which permits pivotally displacement of the neck 25 with sound box 27, to sustain the latter dis- 110

engaged from the record or turn table when out of use. The mouth of the sound box which includes the usual annular diaphragm 28 of mica or equivalent material clamped 5 in place at its rim and actuated from the stylus 29 may be telescoped into neck 25 in the usual manner.

In the preferred embodiment the usual tone arm described is cast with an integral 10 inlet or nipple 30 axially aligned with inlet or nipple 24, and extending diametrically opposite thereto, and serving as a mount for a telephone receiver of suitable construction. The receiver shown in Fig. 2 is substantially of the usual head set type and includes a casing 31 which may be of vulcanite within which is mounted the electromagnetic telephone coil 32 the terminals of which are shown at 33. The magnetic diaphragm 34 is confined by a cap 35 threaded at 36 upon the casing and formed in the embodiment shown, with an integral threaded socket 37 to be threaded over the nipple 30. The end of socket 37 preferably forms 20 a metal to metal bottoming engagement with the shoulder 38 at the base of the nipple.

Preferably the nipple 30 is also adapted 25 alternatively to mount the familiar phonograph loud speaker attachments constituting an article of commerce and which are intended to be substituted for the sound box in order to adapt a phonograph as a radio loud speaker. For this application, as 30 will be seen in Fig. 3, the loud speaker attachment neck 39 is simply telescoped by a friction-fit into the nipple 30, the end of said neck preferably bottoming against a shoulder 40 formed at the inner end of said nipple.

Thus, my tone arm may be used either 35 with a head set receiver that has a special socket threaded exteriorly over nipple 30, or with the usual loud speaker phonograph attachment, the neck of which is telescoped into the nipple 30.

It will be seen that the loud speaking 40 telephone receiver shown in Fig. 3 exposes the usual small central area of diaphragm 50 into effective transmitting or amplifying relation, while the less powerful head set receiver shown in Fig. 2 exposes a larger area of diaphragm, for projecting into the tone arm a greater proportion of the vibratory energy impressed thereon.

It will of course be apparent that a telescoping friction fit mount of the telephone receiver may be substituted for the threaded attachment shown in Fig. 2 and that instead of the friction mount shown in Fig. 3, a threaded mount may be employed as in Fig. 2. It will also be understood that although the metal to metal engagement shown in the drawings is sufficiently tight 55 for ordinary use, compressible washers or

gaskets may be employed in the well understood manner, to assure a sound tight connection.

The sound box and the telephone receiver both remaining affixed to the tone arm at all 70 times whether the apparatus is used as a phonograph or as a radio loud speaker, the connecting joint for the sound box is not likely to wear loose as in constructions in which the sound box must be slipped out 75 and the loud speaker attachment slipped onto the tone arm whenever the phonograph is to be used for radio reception, and, vice versa, to restore the apparatus for phonograph use. Moreover the likelihood of mislaying or injuring the separated sound box or receiver, or of scratching furniture therewith, is wholly obviated in my construction, in which there is no occasion to remove 80 from the tone arm either the sound box or 85 the telephone receiver.

The apparatus is used as a phonograph in the ordinary manner, it being noted that since the entire weight of the tone arm and associated apparatus is supported at the 90 thrust bearing 17, the weight of the telephone receiver at the outer end of the tone arm will not add to the pressure of the stylus 29 against the record R. The telephone receiver casing 31 moreover affords a convenient handle for manipulating the tone arm in starting a record. When the record selection is completed the sound box may be thrown back to inoperative position by pivoting about its mount 26 without interference 95 with the telephone receiver 31.

To employ the apparatus as a radio loud speaker the receiving set is connected to the terminals 33 of receiver 31, with the tone arm in any desired position. The vibrations 100 of the telephone diaphragm 34 are amplified in the tone arm 14 and the amplifier 13 in the usual manner.

I have found that in my construction and arrangement embodying both the sound box and telephone receiver the quality and clearness of the operation is distinctly improved, both in phonograph and in radio 110 loud speaker operation. It seems probable that in the operation as a phonograph some 115 of the vibrations from the diaphragm 28 are transmitted through the connecting air column to the magnetic diaphragm 34 and that in the operation as a radio receiver, vibrations 120 impressed on the magnetic diaphragm 34 are similarly transmitted to the sound box diaphragm. It would appear that in each case the diaphragm upon which the vibrations are impressed would induce in the other diaphragm vibrations in synchronism or substantially in synchronism therewith, and that this causes the mellowed or enriched tone quality noted.

My apparatus is also susceptible of a use 125 which I believe is broadly new, for conjoint 130

- or simultaneous phonographic and telephonic or radio amplification through the phonograph amplifier. A phonograph record might for instance be played while the same selection is received in synchronism therewith upon the radio set, both the record reproduction and the telephonically transmitted vibrations being projected through the phonograph amplifier. In another specific application, a vocal selection received on the radio set might be amplified by the phonograph in synchronism with the corresponding musical accompaniment played on the record.
- 15 My invention is also an instrumentality for a distinctly novel entertainment. A phonograph musical record without vocal accompaniment may be played, for instance, and thereupon the entertainer may play the same record which now appears to include a vocal accompaniment, the latter produced by an assistant in an adjoining room who now sings the accompaniment into a telephone transmitter which is connected in a wired telephone circuit with the receiver 31 on the telephone.
- Other interesting, surprising or ludicrous effects may be produced in manners apparent from the foregoing.
- 30 It will thus be seen that there is herein described apparatus in which the several features of this invention are embodied, and which apparatus in its action attains the various objects of the invention and is well suited to meet the requirements of practical use.
- As many changes could be made in the above construction and many apparently widely different embodiments of this invention could be made without departing from the scope thereof, it is intended that all matter contained in the above description or shown in the accompanying drawing shall be interpreted as illustrative and not in a limited sense.
- Having thus described my invention, what I claim is new and desire to secure by Letters Patent is:—
- In a tone arm, for a combined phonograph and radio receiving apparatus, in combination, a pair of support tubes extending in axial alignment horizontally from opposite sides of the outer end of said tone arm a sound box neck attached to one of said tubes and a telephone receiver having a cap with an integral hub in telescoping relation with the other said tube.

Signed at New York, in the county of New York and State of New York, this 13th day of November A. D., 1923.

WILLIAM PHILLIPS.
